UNITED STATES PATENT OFFICE.

ALFRED G. BROWN, OF WINONA, MINNESOTA, ASSIGNOR TO UNION FIBRE COMPANY,
OF WINONA, MINNESOTA, A CORPORATION OF MINNESOTA.

REFRIGERATOR-CAR.

982,571.

Specification of Letters Patent. Patented Jan. 24, 1911.

Application filed September 27, 1909. Serial No. 519,754.

To all whom it may concern:

Be it known that I, ALFRED G. BROWN, of Winona, in the county of Winona and State of Minnesota, have invented a certain new and useful Improvement in Refrigerator-Cars; and I do hereby declare the following to be a full, clear, and exact description of the same, reference being had to the accompanying drawings, forming a part of this specification, and to the figures and letters of reference marked thereon.

This invention relates to refrigerator cars, particularly cars of that class which are designed for handling perishable goods of various kinds, in some instances requiring the use of ice for purposes of refrigeration and in other instances requiring a full and free ventilation for the preservation of goods.

20 The objects of the invention are to provide a structure with which either a full or free ventilation may be secured without permitting access to the interior of the car either by unauthorized persons or by rainwater or with which the car may be closed for ice refrigeration, the structure being such that when used under ventilating conditions the ice bunker or receptacle may be folded completely out of the way so as to 30 provide an increased cargo space.

A further object of the invention is to so arrange the ice bunker and interior construction of the car that an effective circulation of the air is insured within the cargo space 35 when the car is traveling either under ice or with ventilation from the exterior.

Referring to the accompanying drawings—Figure 1 is a longitudinal section through one end of a car embodying the 40 present improvements. Fig. 2 is a transverse section in a vertical plane in front of the ice bunker and with a portion of the front wall of said bunker broken away. Fig. 3 is a section in a horizontal plane 45 taken through the lower part of the front wall of the ice bunker. Fig. 4 is a detail of one of the retainers for the front wall of the bunker.

50 Similar letters of reference in the several figures indicate the same parts.

The flooring, walls and roof of the car are of ordinary construction and indicated generally by the letter A. The ice bunker is arranged at one end of the car or, if two bunkers are employed, one is located at each

end of the car. The bunker is made to fold or collapse with its front wall parallel to and in proximity to the end wall of the car itself.

In the preferred construction the front 60 wall B of the bunker is made solid, that is to say imperforate except for a central tightly closing door or trap B' through which access to the interior of the bunker may be had from the cargo space. This 65 front wall B terminates at the bottom a short distance above the floor of the car and is preferably provided with end posts C having rollers c at the lower end and a central roller c' on which the wall may be 70 moved bodily toward and from the end wall of the car. Filling pieces D may be introduced between the end posts C and side walls of the car and, as a matter of convenience, the said posts C may be of channel iron and 75 packing strips D' of doubled canvas or suitable flexible material may be secured to the channel irons and project into contact with the side walls of the car to close the spaces between the sides of the bunker front and 80 side walls of the car.

Lateral stability of the front wall of the bunker is secured by diagonal braces E and the said wall is maintained in its vertical position parallel with the end walls of the 85 car by a plurality of jointed links F pivotally connected at one end with the front wall and at the opposite end with the end wall of the car. The joints between the sections of the links may be conveniently connected by a vertical strip or bar G whereby 90 all of said links will be folded or deflected upwardly as indicated by dotted lines in Fig. 1 and at the same time the said strip or bar G at its lower end is adapted to come in contact with the floor of the car so as to limit the downward movement of the proximate ends of the links when the front wall of the bunker is in its extended position, as shown by the full lines in Fig. 1. 95 These jointed links and their connecting bars are preferably arranged at opposite ends of the ice bunker or in proximity to the side walls of the car, as will be readily understood from an inspection of Figs. 1 and 3, whereby obstruction in the ice space of the bunker is reduced to a minimum and the parts are less liable to be distorted by being struck by heavy blocks of ice.

100 To support the blocks of ice and permit of 105

a free ventilation through the bottom of the bunker, bunker bottom bars II are hinged at h to the end wall of the car and at their outer or free ends are adapted to rest upon 5 and hook over brackets h' secured to the inner face of the front wall B. The number of slats employed to form the bottom of the bunker should be sufficient to prevent the passage of ice through between the same 10 and it will be understood that they may be connected to form floor grids, two or more being preferably employed each capable of being folded up flat against the end wall of the car or of being turned down and supported at the outer or free edge by brackets h' on the inner face of the front wall of the 15 bunker.

For locking the bunker in its extended position, shown in full lines in Fig. 1, the said 20 front wall is preferably provided with locking bolts, indicated at I, adapted to be operated by a pinion i to the shaft i' of which a suitable key or handle may be applied from the cargo space of the car.

25 The links to which the front wall of the bunker is jointed preferably have rule joints and will ordinarily be sufficient to hold the wall in proper extended position without the use of the locking bolts but it is desirable to 30 always employ some means for holding the wall positively in its folded position.

For holding the bunker wall at the bottom, I employ a hook R on the frame at the end of the car and a staple or cross-bar r at 35 the center of the bunker wall with which the hook automatically engages when the bunker wall is pushed in. At the top two catches are provided, one at each corner. These catches lettered S are preferably pivoted at 40 s to the side walls of the car, (see Fig. 4) so as to be movable for the passage of the bunker wall to its closed position and requires to be moved by hand to release the said wall. If desired, they may be moved 45 over a projection s' so as to be held in either operative or inoperative position.

When in its extended position, the upper edge of the front wall of the bunker rests against or in proximity to the edge of the 50 ceiling K of the cargo space of the car and between the said ceiling K and roof A a ventilating space is formed which, preferably, gradually contacts in width away from the bunker end of the car. The end of the space 55 remote from the bunker is left open at k' and apertures k of smaller size than the opening k' in the ceiling K, permit the entry of warm air which is conducted through said space toward the end of the 60 car and into the ice bunker where, when ice is present, it is cooled and drops by gravity through the bottom of the bunker and flows out beneath the front wall into the cargo space of the bunker. This circulation is 65 maintained so long as the air passing

through the bunker is cooled by the ice and air in the cargo space is raised to a higher temperature either by products within the cargo space or by external atmospheric conditions.

70 For the purpose of permitting the charging of the bunker with ice and also for ventilation purposes when the car is not traveling under ice, a hatchway or opening L is formed in the roof of the car, preferably at 75 one side of the center, as shown in Figs. 1 and 2, which hatchway is adapted to be closed by a tight fitting plug or cover L' but, inasmuch as this hatchway is liable to afford a means of access to the car both by unauthorized persons and by rain-water, a hood 80 is provided which may be locked in position over and around the hatchway and its cover, or when the car is to be iced, the said hood may be moved out of the way, as indicated 85 for instance in dotted lines, Fig. 1. In the preferred construction, the hood is made with solid top, rear and end walls M and its face toward the end of the car is formed with two sets of slats m' and m^2 , respectively, the slats m^2 , which are on the inner side of the slats m' , being inclined at a somewhat steeper angle so as to effectually exclude water which may be driven through 90 between the slats m' . The water is conducted 95 downwardly into a drip trough N which discharges at a suitable point on the roof of the car. In addition, the entrance opening to the hood is provided with a fine mesh screen O which will serve as a filter for the 100 entering air and will also catch and conduct down to the drip trough any water or moisture which may drive through between the slats. For convenience, the rear wall M' of the hood is inclined and when the car is 105 proceeding under ventilation the plug or hatchway cover L' is drawn up against the inclined wall M' by a central chain l where it may be held by a staple l' and suitable lock, if so desired. In this position it serves 110 as a deflector for the air entering through the front end of the hood which air is thereby deflected down into the body of the car and by circulating through the same serves to preserve the cargo when the latter is of 115 such character as to not require the employment of ice. The hood itself is adapted to be locked in position over and around the hatchway by a hasp and staple n through which a suitable pad-lock may be passed, 120 and it is preferably mounted to slide rearwardly to uncover the hatchway in ways or tracks T, small rollers or wheels t being interposed, if desired, to facilitate the movement.

125 As an additional precaution against the entry of unauthorized persons to the cargo space of the car when the ice bunker is collapsed, the front wall of said bunker is provided with a horizontally extending screen 130

P of large mesh which screen is adapted to be moved in across the hatchway opening with the front wall of the bunker when the latter is moved toward the end wall of the car, as will be readily understood from inspection of Fig. 1.

When the bunker is collapsed the outer edge of the screen P is held by catches or hooks p of any desired or preferred character.

When it is desired to utilize the full cargo space of the car for goods not requiring ice refrigeration the ice bunker is collapsed and, if desired, the hatchway is opened for the entrance of external air, as before described but, should ice be required, the bunker is extended to the position shown in full lines in Fig. 1 and for charging the bunker the hatchway hood is moved back to the position indicated in dotted lines. After the bunker is charged the hood is moved forwardly to the position shown in full lines and locked, after which the hatchway may be closed by its plug or cover L' and refrigeration will take place by the natural circulation of the air within the cargo space and bunker, there being an effectual separation of the streams of air proceeding from and toward the bunker. By the provision of a plurality of series of apertures in the ceiling K, with the main opening at a point remote from the bunker, short-circuiting of the air currents is prevented and an effectual distribution of the cool air to all parts of the cargo space is insured.

Having thus described my invention, what I claim as new and desire to secure by Letters Patent of the United States, is:—

1. In a refrigerator car, the combination with the walls inclosing the cargo space, of a collapsible ice bunker in the end of said space embodying an upwardly folding bunker bottom adapted in folded position to lie flat against the end wall of the car, a bunker front wall movable bodily toward and from said end wall and independent sets of jointed links located and movable in vertical planes beyond the ends of the folding bottom and connecting said end and front walls, whereby the front wall is held in parallelism with the end wall and an unobstructed ice space is left between the links and above the

bottom when the parts are in extended position.

2. In a refrigerator car, the combination with the walls inclosing the cargo space, of a collapsible ice bunker in the end of said space embodying an upwardly folding bunker bottom adapted in folded position to lie flat against the end wall of the car, a bunker front wall movable bodily toward and from said end wall and independent sets of jointed links located and movable in vertical planes beyond the ends of the folding bottom and connecting said end and front walls, the links of each set being connected together at a point intermediate their ends to move in unison.

3. In a refrigerator car, the combination with the walls inclosing the cargo space, of a collapsible ice bunker in one end of said space embodying an imperforate movable front wall, and an air circulating flue in the top of the cargo space with the bottom of which the wall of the bunker engages when extended whereby the flue discharges into the bunker.

4. In a refrigerator car, the combination with the walls inclosing the cargo space and a ceiling for said space forming an air circulating flue, of a collapsible ice bunker having a front wall movable bodily toward and from the end wall of the car and having its top in position to form a continuation of the air circulating flue when moved outwardly whereby said flue is caused to discharge into the ice bunker.

5. In a refrigerator car, the combination with the walls inclosing the cargo space, of a collapsible ice bunker embodying an imperforate front wall, a plurality of jointed links at opposite ends of the ice space, said jointed links connecting each side edge of said bunker wall and end wall of the car, means connecting the links on each end and extending downwardly for limiting the downward movement of the joints of said links, and means for supporting the bunker wall in its movements toward and from the end wall of the car.
